DECK OF PLAYING CARDS

Abe R. Brothers, 900 Jefferson Ave., Brooklyn, N.Y.

Filed Nov. 3, 1964, Ser. No. 82,446

Term of patent 14 years

(Cl. D34—13)

The figure is a plan view of a set of playing cards showing my new design. The cards are of conventional thickness and the backs are plain and conventional. The characteristic features of my design reside in the combination on a playing card of the circular apertures and the particular arrangement of pips, all as shown.

I claim:

The ornamental design for a deck of playing cards, as shown and described.
